ROBERT D. LEARY, OF WORCESTER, MASSACHUSETTS.

CELLULOID RECEPTACLE.

Specification of Letters Patent. Patented Feb. 29, 1916.

1,173,282.

Application filed January 12, 1915. Serial No. 1,743.

To all whom it may concern:

Be it known that I, ROBERT D. LEARY, a citizen of the United States, residing in the city of Worcester, county of Worcester, State of Massachusetts, have invented a certain new and useful Celluloid Receptacle, of which the following is a specification.

This invention is a celluloid receptacle, and the object of the invention is to overcome certain disadvantages inherent in articles of this character as heretofore constructed, and, more particularly, with reference to the manner of pivotally securing the cover to the receptacle.

As is well understood, sheet celluloid, such as is used in making receptacles, is so frail and brittle as to render it very difficult to form durable hinge members, clasps, and other parts subjected to strain. Moreover, it has been the practice, heretofore, to make the parts referred to separately, and to subsequently secure them to the respective portions of the receptacle, particularly when a strong and durable construction is desired.

The present invention overcomes the disadvantages referred to, and others, in that it embodies a receptacle wherein the hinge members, clasps, etc., are integral with their respective parts of the receptacle, thereby dispensing with making the features referred to separately, as well as providing a more rigid receptacle, and permitting, if desired, the employment of thinner sheet material than is customarily employed, and without sacrifice of strength.

The specific embodiment of the invention herein described is a toilet article, and the receptacle constitutes a handle for a tooth brush, but it will be understood that the invention is not limited to said specific embodiment.

Features of the invention, other than those described, will appear from the herein-after detailed description, taken in conjunction with the accompanying drawings.

In the accompanying drawings, I have illustrated one practical embodiment of the invention, but the construction shown therein is to be understood as illustrative, only, and not as defining the limits of the invention.

Figure 1 is a perspective view illustrating a receptacle embodying the present invention, said receptacle being shown with the cover in opened position. Fig. 2 is a perspective view illustrating the container

which forms the body of the receptacle, said container being shown with the cover detached, and one side thereof being shown as it appears before the finishing operation in making the same. Fig. 3 is a face view of a blank from which the cover of the receptacle is formed. Fig. 4 is a transverse section of the completed cover, said section being taken in the plane of the line 4-4 of Fig. 3, and 65. Fig. 5 is a like section taken through the container in the same plane as illustrated by line 4-4 in Fig. 3.

Referring to the drawings, A designates the body which forms the container of the receptacle. This container is shown as shaped to serve as a handle for a toilet article of the general character disclosed in my allowed application Serial No. 809,154, filed Dec. 29, 1913, allowed September 16, 75 1914. According to the invention referred to, a tooth brush or other toilet article is pivoted on the pindle a, and is adapted to be infolded into the receptacle A, or positioned exteriorly and in alinement therewith, in which case the receptacle A serves as a handle for the toilet article. The container A is thus shaped to contain the toilet article to its best advantage, and the cover B is hinged at one side of the container so 80 as to fold down over the same and form a closure therefor.

The side C of the container A to which cover B is pivoted is, according to the present invention, initially made substantially twice its required height, as shown in Fig. 2 of the drawings, and alined, longitudinally disposed, apertures c are formed in said side substantially in the plane of the top of the container A. If side C is now 90 folded downwardly upon itself at the line D-D, after the manner shown in Fig. 5, loops d will be formed by the uncut portions e' of side C, and through this loop the pivot pin d, by means of which the cover B is 100 pivotally secured to the container, is attached. Side C of the container may be secured in its folded over position by any suitable means, such as an adhesive, rivets, or the like.

In forming the cover B to the receptacle, the same is preferably produced from a blank G, such as that shown in Fig. 3 of the drawings in which figure line F denotes the medial line of the blank. Blank G is cut 110 away, as at g along the medial line thereof so that when the blank is folded on said

medial line, shown in Fig. 4, loops g^2 are formed by the uncut portions g' intermediate the cutaway portions g , which loops g^2 are adapted to receive the pivot pin d' , hereinbefore referred to. When the loops g^2 of cover B are interlocked with loops d , the pivot pin d' may be passed alternately through loops d and g^2 for the purpose of pivotally securing the cover to the container.

Although it is not essential, I preferably provide one edge of blank G with a projecting tab H having an aperture h. After blank G has been folded upon itself to form the loops for the pivot pin, this tab H may be folded on line I—I, at substantially right angles to the plane of the cover, as shown in Fig. 4, the function of this tab being to engage with the projection h' on the container A to form a clasp, or catch to maintain the cover in its closed position. It will be understood that after blank G has been folded on the medial line F, the parts thereof may be secured together similar to the manner in which the parts of side C are secured together, as hereinbefore described.

It will be manifest from the foregoing that the structure described is extremely simple in construction, and may be easily assembled. Moreover, the finished receptacle is of maximum strength, as excessive strains on the hinge members are transmitted to the respective portions of the receptacle over large areas. Moreover, it is impossible for excessive strains to unroll or straighten out the loops forming the hinge members as is commonly the case in celluloid receptacles as now constructed, since the normally free ends of said hinge members are so far removed from the strain at the hinge pin as to render this impossible. I preferably make the side c of the container to which the cover is pivoted of such initial length that, when it is folded down, its free edge abuts the bottom of the container. In like manner, the cover is preferably so constructed that it will be of double thickness throughout its entire extent. I may, however, if I desire, modify this somewhat—e. g., the inside ply of the cover may be cut away to such extent that when the cover is in closed position, the inside ply will come within the container A, and the outside ply rest on the open edge of said container. In this manner a half lapped joint is secured, thereby greatly stiffening the sides, and at the same time precluding dust or dirt from entering the closure.

A salient feature of the invention, from a commercial standpoint, resides in the fact that the making of the cover or the side of the container, to which it is pivoted, of a plurality of plies, enables the same to be formed from material of much lower gage than it has heretofore been possible to em-

ploy. This is, of course, largely due to the fact that the strain transmitted by the hinge or pivot pin is so widely distributed over the material.

It will, of course, be understood that while I have shown and described the present invention as particularly adapted for use in making the inclosing casing for toilet articles, it is manifest that the invention is not restricted to this specific use, and it will further be obvious that slight changes may be made from time to time in adapting the invention to its different environment. Accordingly, I do not restrict myself to the specific structure or details shown, but wish it understood that my invention is broadly novel, as is commensurate with the appended claims.

Having thus fully described the invention, what I claim as new, and desire to secure by Letters Patent is:

1. A closure embodying a sheet of celluloid provided intermediate its lateral edges with an aperture, a portion of which sheet is folded upon itself, the line of folding passing through said aperture whereby laterally projecting hinge members are formed at either end of said aperture, through which hinge members a pin may be passed for the purpose of securing the closure to a hinge member adapted to be inserted into the opening between the hinge members of the closure.

2. As a new article of manufacture, a celluloid receptacle one of the sides of which embodies a double ply of material, a cover also embodying a double ply of material, and a pivotal connection between the cover and said side of the receptacle, the pivot pin of which connection is positioned between the plies of the material.

3. As a new article of manufacture, a celluloid receptacle having a body member, a cover for said body member embodying a plurality of plies of material, a pivot pin positioned between the plies of the cover, portions of which cover are cut away to expose the pivot pin, and means positioned on the body member and extending through the cut-away portions of the cover into engagement with the pivot pin whereby the cover is pivotally secured to the body of the receptacle.

4. As a new article of manufacture, a receptacle comprising a container and a closure pivoted thereto, the closure embodying a plurality of plies and that portion of the container to which said closure is pivoted also embodying a plurality of plies, and a pivot pin positioned intermediate the plies of both the closure and the multi-ply portion of the container for the purpose of pivotally securing said closure to the container.

5. As a new article of manufacture, a re-

ceptacle comprising a container and a closure pivoted thereto, the closure embodying a plurality of integral plies and that portion of the container to which said closure is pivoted also embodying a plurality of integral plies, and a pivot pin positioned intermediate the plies of both the closure and the multi-ply portion of the container for the purpose of pivotally securing said closure to the container.

6. As a new article of manufacture, a receptacle comprising a container and a closure pivoted thereto, the closure embodying a plurality of plies and that portion of the container to which said closure is pivoted also embodying a plurality of plies, portions of the closure, as well as portions of the multi-ply portion of the container, being cut away, whereby part of the closure is adapted to interlock with a part of the container, and a pivot pin positioned between the plies of the interlocking portions of the closure and the container for the purpose of pivotally securing said closure to said container.

7. A closure embodying a sheet of celluloid, a portion of which is adapted to be folded over to render a part of the closure of double thickness, said sheet of celluloid being cut away intermediate its edges on the line of folding to allow of the insertion of a hinge member into the cut-away portion of the closure, which hinge member is adapted to be secured to the closure by passing a pin between the folds thereof and through said hinge member.

8. A blank from which a receptacle cover may be formed, said blank embodying a sheet of celluloid substantially twice the width of the cover desired, said sheet being adapted to be folded on its medial line to

form a two-ply cover, and being cut-out along its line of folding to form laterally projecting hinge members adapted to receive a pivot pin, whereby said cover may be pivotally secured to a receptacle.

9. A receptacle body, one side of which is formed substantially twice the required height and thereafter folded down upon itself to form that portion of the receptacle of double thickness, said portion of the receptacle being cut away at spaced distances along the line of folding thereof to produce spaced projecting hinge members, and a pivot pin position within said folded-over portion and adapted to alternately extend through the projecting hinge members and bridge across the cut-away portions intermediate said hinge members, whereby a cover having complementary hinge members may be pivotally secured to the receptacle.

10. A blank from which a receptacle cover may be formed, said blank embodying a sheet of celluloid substantially twice the width of the cover desired, and having a projecting tab along one edge thereof, said sheet being adapted to be folded on its medial line to form a two-ply cover, and being cut out along its line of folding to form laterally projecting hinge members adapted to receive a pivot pin, whereby said cover may be pivotally secured to a receptacle, the projecting tab being adapted to be folded in angular relation to the cover for the purpose of forming a catch member.

In testimony whereof I have signed my name to this specification in the presence of two subscribing witnesses.

ROBERT D. LEARY.
